UNITED STATES PATENT OFFICE.

HARRY C. MALLORY, OF NEW YORK, N. Y.; SUE R. MALLORY ADMINISTRATRIX OF
SAID HARRY C. MALLORY, DECEASED.

ENGINE-COOLING SYSTEM.

Application filed July 2, 1921. Serial No. 482,090.

To all whom it may concern:

Be it known that I, HARRY C. MALLORY, a citizen of the United States, and resident of New York city, in the county of New York and State of New York, have invented certain new and useful Improvements in Engine-Cooling Systems, of which the following is a specification.

My present invention comprises improvements in that type of engine cooling system specially adapted for use with automobile and analogous internal combustion engines in which practically all, or at least the major portion of the heat abstracted from the engine by the cooling liquid is normally utilized in vaporizing the cooling liquid and is dissipated in a condenser in which the vapor is condensed.

The general object of the present invention is to provide improved apparatus for the purpose specified characterized in particular by the simplicity of the piping and of the provisions for maintaining an adequate supply of cooling liquid in the cooling space under varying conditions of use. In the preferred mode of carrying out my invention I provide means for storing an excess of liquid in a suitable container, which serves as the condenser hot well and may be formed in whole or in part by the lower portion of the condenser shell. Liquid of condensation formed in the condenser and liquid flowing into the condenser from the jacket drains into this container. From this storage space I pump the cooling liquid into the engine jacket, preferably at or adjacent its bottom, at a rate exceeding that at which liquid is vaporized in the engine jacket. At the top of the jacket I provide an outlet through which liquid and any vapor formed in the jacket pass to the top of the condenser. The condenser preferably differs from the ordinary radiator of a water cooled system by having provisions for diverting the water entering the top of the condenser away from the condensing tubes or other condensing surfaces into channels running down to the condenser hot well and serving as flow paths for the water and as vapor distributors.

The various features of novelty which characterize my invention are pointed out with particularity in the claims annexed to and forming a part of this specification.

For a better understanding of the invention however, and the advantages possessed by it, reference should be had to the accompanying drawings and descriptive matter in which I have illustrated and described a preferred embodiment of my invention.

Of the drawings:

Fig. 1 is an elevation with parts broken away and in section of one form of my improved cooling system;

Fig. 2 is a section on the line 2—2 of Fig. 1;

Fig. 2^A is an enlarged front end elevation drawn approximately to scale of a portion of the condenser shown diagrammatically in Figs. 1 and 2;

Fig. 3 is an elevation taken similarly to Fig. 1 of a portion of a modified arrangement; and

Fig. 4 is a section on the line 4—4 of Fig. 3.

In the drawings and referring first to the construction shown in Figs. 1 and 2, A represents the cooling liquid jacket for the cylinders A⁵ of an ordinary internal combustion automobile engine. An inlet A' is provided at the bottom of the jacket space for the cooling liquid which will ordinarily be water, or a water and alcohol mixture, and A² represents the outlet for vapor which also serves as the overflow outlet for the cooling fluid. In the particular arrangement shown in Figs. 1 and 2, the outlet A² opens from the end of the jacket space near its top and is of substantial size. The outlet A² is connected by a conduit C which may include the usual flexible coupling C' to the upper portion of the condenser. Interspersed through the condensing space or interior of the condenser are the usual condensing surfaces which may be of any usual or suitable type. For automobile use the condenser may well be formed, as shown, like the radiator of the usual water circulating cooling system, namely, with horizontal small diameter tubes B' closely spaced to provide horizontal passages for atmospheric air which is drawn through them from the front to the rear of the condenser by the usual fan G', the ends of the tubes being expanded and soldered together to form the corresponding portions of the condenser shell.

In the form of my invention shown in

Figs. 1 and 2 the tubes B' are omitted from portions of the condenser to provide an open space B² into which the conduit C opens, vertical passages B³ at the sides of the condenser, and a water receiving space or hot well B⁴. A baffle E⁹ at the bottom of the space B² deflects water and steam entering the condenser from the conduit C into the passages B³, which serve as steam distributing channels and also form flow paths for water passing to the hot well or water space B⁴. Advantageously the condenser is provided with suitably disposed baffles or rain plates R which serve to deflect water of condensation formed on the condensing surfaces above them away from the condensing surfaces beneath them and into the passages B³. The water space B⁴ in the bottom of the condenser shell is connected to the water inlet A' of the jacket by a conduit D including a pump E. Advantageously, in some cases, the conduit D is formed as shown with a goose neck portion D' extending to the water level which it is desired to maintain in the jacket to prevent the jacket from draining when the pump is stopped. To prevent siphon draining the goose neck should be vented as by means of the vapor pressure equalizing connection F from the top of the goose neck into the condenser B. The pump E is driven, in the construction shown, from the engine shaft through a reduction gear conventionally illustrated at E' and through which the driving belt G for the fan G' is also driven.

Preferably provisions are made for admitting air to and withdrawing air from the condenser as disclosed in my prior application No. 163,332 and No. 473,439 to thereby vary the capacity of the condenser as required to maintain an approximately constant vapor pressure and temperature in the condenser notwithstanding variations in engine load and in the temperature of the external atmosphere. The means shown for this purpose comprises an air pipe H connected through a steam trap I to the suction intake manifold L of the engine to thereby exhaust air from the condenser as required to maintain a minus pressure therein. As shown the pipe H projects into the condenser shell and is formed with an air inlet H' at its under side through which air may enter the pipe from the intertube space, but into which water of condensation draining down from the condensing tubes B' will not fall. The minus pressure thus maintained is fixed by the adjustment of a vacuum relief valve K which automatically opens to admit air to the condenser when the pressure of the atmosphere exceeds the pressure in the condenser by a predetermined amount. Advantageously the air pipe is of appreciably larger size than the

tubes B' and has expanded portions H² shaped to take the place in the end walls of the condenser shell of the expanded end portions of a group of say seven tubes B' as shown in Fig. 2. The front end of the pipe H is closed. A plug cock H³ may be provided in the pipe which can be closed when this is desirable. M represents a safety valve attached to some part of the circulating system which opens and permits the escape of vapor or liquid when, from any cause, the pressure in the circulating system exceeds a predetermined amount. The walls of the condenser hot well and of the channels B³ may be insulated to minimize heat losses.

In the preferred mode of use contemplated of the apparatus shown in Figs. 1 and 2, the unvaporized liquid passing into the condenser through the conduit C runs off the ends of the baffle B¹⁰ into the channels B³ and falls through the latter into the water space B⁴. The steam entering the space B² also passes into the channels B³, and is distributed by the latter into the intertube space. The liquid of condensation formed above the baffles R drains into the space B⁴ through the channels B³ while the water of condensation formed below the baffles R drains directly into the space B⁴. When the apparatus shown in Figs. 1 and 2 is operated in the manner described, the temperature at the top of the jacket will be maintained approximately constant at a value determined by the setting of the vacuum relief valve K, notwithstanding variations in engine load or of the temperature of the cooling air drawn through the condenser by the fan G'.

When the connection C is upwardly inclined from the top of the jacket condenser as shown in Figs. 1 and 2 as is necessary or at least desirable in adapting the invention to certain types of engines, the liquid level in the system will be practically at the bottom of the discharge end of the conduit C and may be well above the top of the jacket. In this case some of the vapor generated by the heat absorbed from the jacket will be liberated in the vapor space above the liquid level in the discharge end portion of the connection C, but under heavy load conditions, much of the vapor generated will be entrained in the boiling water entering the condenser, and will separate from the water in the condenser space B². Where the type of engine employed or other conditions makes it possible to provide a vapor space in the top of the jacket itself and to horizontally dispose the pipe C connecting the top of the jacket with the top of the condenser, this may advantageously be done. In such case the liquid level in the system will be well below the top of the jacket as shown in Figs. 3 and 4 and liquid will then

normally overflow from the top of the jacket into the condenser along the bottom of the conduit C while vapor will flow through the upper portion of the conduit. 8 The relative amounts of liquid and vapor entering the condenser may vary through wide limits without changing the character of the operation appreciably, and with the system filled with water and the cock H' 10 adjusted to close the air pipe H, the system shown in Figs. 1 and 2 will operate as a water cooled system.

Ordinarily the system is initially supplied with water as through the opening normally 15 closed by the safety valve M to fill the jacket and conduit C to the overflow level, and to fill the hot well to a level somewhat below the air exhaust connection H. After the jacket is initially filled, additional liquid 20 may be supplied from time to time as required to make up leakage loss. It will be apparent that with the jacket full and the hot well partly filled, the system contains a considerable amount of liquid in excess of 25 that required for operation, and considerable leakage of liquid or vapor may occur from the system before replenishment becomes necessary. The amount of excess liquid which may thus be stored in the hot 30 well depends of course upon the dimensions of the latter.

Where to get increased capacity, or for other reasons, it is desirable to have the top 35 of the condenser appreciably above the outlet A' from the engine jacket, the space B' of the condenser into which the outlet is connected may be located between upper and lower groups of tubes B' as in the condenser D' shown in Figs. 3 and 4. With a 40 single fan, and with the central arrangement of the conduit C shown in Figs. 3 and 4, the portion of the condenser above the inlet will be relatively less effective than the lower portion of the condenser but nevertheless 45 may add appreciably to the total capacity of the condenser. In the construction shown in Figs. 3 and 4 the air exhaust piping H comprises one branch opening to the bottom of the condenser as in Figs. 1 and 2, 50 and a second branch opening to the space B'.

In both forms of my invention illustrated, if a constant vapor pressure is maintained in the condenser, an approximately constant 55 pressure and a correspondingly constant temperature will be maintained in the engine jacket under all conditions of operation. The provisions made for introducing liquid into the jacket at a rate in excess of 60 that at which liquid is vaporized by heat absorbed in the jacket not only insures a liquid circulation through the jacket, but insures an adequate amount of liquid in the jacket at all times. The return connection 65 for unvaporized liquid thus forms a simple

and effective overflow device. To prevent all possibility of the direct flow of steam through the passages B³ and B⁴ to the air outlet port H', baffles S may be provided as shown in Fig. 4 to provide water seals between the lower ends of the channels B³ and the portion of the space B⁴ immediately beneath the air pipe H. 70

While in accordance with the provisions of the statutes I have illustrated and described the best forms of my present invention now known to me, it will be apparent to those skilled in the art that changes may be made in the form of my invention without departing from the spirit of my invention as set forth in the appended claims, and that certain features of my invention may sometimes be used to advantage without a corresponding use of other features. 75

Having now described my invention, what I claim as new and desire to secure by Letters Patent, is:

1. In a cooling system, the combination with a liquid cooling jacket having a top outlet, of a surface condenser comprising distributed condensing surfaces, a connection from said outlet to the upper portion of the condenser for passing liquid and vapor into the latter, means within the condenser for diverting liquid away from the condensing surfaces and a pump for passing liquid from the bottom of the condenser into said jacket. 80

2. In a cooling system, the combination with a liquid cooling jacket having a top outlet, of a surface condenser, comprising distributed condensing surfaces arranged to provide one or more steam distributing channels leading downward past the condensing surfaces, a connection from said outlet to the upper portion of the condenser for passing liquid and vapor into the latter, means within the condenser for diverting liquid away from the condensing surfaces and into said channels, and a pump for passing the liquid from the bottom of the condenser into the jacket. 100

3. In a cooling system, the combination with a liquid cooling jacket having a top outlet, of a surface condenser comprising distributed condensing surfaces arranged in upper and lower groups, a connection from said outlet to the condenser opening to the latter between said groups of condensing surfaces through which liquid and vapor pass into the condensers, means within the condenser for diverting liquid away from the lower group of condensing surfaces, and a pump for passing liquid from the bottom of the condenser into said jacket. 115

4. An engine cooling condenser comprising a plurality of parallel tubes spaced apart and having their end portions connected together to form walls closing the ends of the intertube space and having an opening in 120

the wall of one of said tubes whereby the latter forms a connection to the intertube space of the condenser.

5. An engine cooling condenser comprising a plurality of small parallel tubes spaced apart and having their end portions expanded and connected together to form walls closing the ends of the intertube space, and a larger tube parallel to the others and assembled with them and having portions forming parts of said walls shaped to take the place of the expanded end portions of a group of the smaller tubes and having an opening in its wall to said intertube space.

6. In a cooling system the combination with a liquid cooling jacket having a top outlet, of a surface condenser comprising distributing condensing surfaces arranged between an upper vapor space and a lower liquid space and arranged to provide one or more distributing channels leading down-

ward past the condensing surfaces from the vapor space to the liquid space, a connection from said outlet to the upper portion of the condenser for passing liquid and vapor into the condenser, means within the condenser for diverting liquid away from the condensing surfaces and into said channels, a pump for passing liquid from the said liquid space of the condenser into said jacket, an air outlet from the condenser above but adjacent the said liquid space, and baffles at the sides of said channels liquid sealed at their lower ends for preventing the direct flow of vapor from the lower ends of said channels through the said liquid space to said air outlet.

Signed at New York city, in the county of New York and State of New York, this 1st day of July, A. D. 1921.

HARRY C. MALLORY.
